Inventor:

Chas P. Bell

United States Patent Office.

CHARLES P. BELL, OF NASHUA, NEW HAMPSHIRE.

Letters Patent No. 64,740, dated May 14, 1867.

IMPROVED WINDOW-BLIND FASTENER.

The Schedule referred to in these Letters Patent and making part of the same.

Be it known that I, CHARLES P. BELL, of Nashua, in the county Hillsborough, and State of New Hampshire, have invented a new and useful improvement on a machine for fastening window-blinds, called "The Model Blind-Fastener;" and I do hereby declare that the following is a full, clear, and exact description of the construction and operation of the same, reference being had to the annexed drawings, making a part of this specification, in which—

Figure 1 is a side view.

Figure 2, a front view.

Figure 3, a bottom view.

Figure 4, the same as fig. 1 with the tube A removed.

Figure 5, a transverse section of the tube A.

Figure 6, a spiral spring.

In the construction of my blind-fastener I use three pieces, the first, a hollow tube, marked A, of cast iron or other metal to be inserted in the bottom of the blind, with two ears on the sides of the lower end of the tube through each of which it is fastened by a screw to the blind. On one side, between the two ears, is a groove running up about five-eighths of an inch from the lower end of the tube. The top of the tube is left uncovered for the upper end of the piece marked B to play through.

The second piece, marked B, consists of a common blind-latch, from the centre of the back of which projects upward a stem which plays in the tube A. From the side of this stem through the above-mentioned groove projects laterally the thumb-piece. This piece may be composed of brass, malleable iron, or other metal.

The remaining piece is a spiral spring, marked C, which works on the upper half of the stem B and inside the tube A, the upper end being confined by the top of the tube, and the lower end resting on the shoulder in the stem. When the blind is closed the spring holds the latch down. The blind is unlatched by raising the thumb-piece.

I do not claim broadly the use of spring-catches, as I am aware that they have been used before, but having thus fully described my invention, what I do claim as new, and desire to secure by Letters Patent, is—

The stem B provided with a thumb-piece on its side, and a catch upon its lower end, when used in combination with the socket or tube A, provided with an opening or slot in its side to receive the thumb-piece, and with a coiled spring, C, which surrounds the stem, as and for the purpose herein specified.

CHAS. P. BELL.
